UNITED STATES PATENT OFFICE.

ARNOLD FREY, OF CHICAGO, ILLINOIS.

HAIR-CUTTING IMPLEMENT.

SPECIFICATION forming part of Letters Patent No. 375,546, dated December 27, 1887.

Application filed August 16, 1887. Serial No. 247,117. (No model.)

To all whom it may concern:

Be it known that I, ARNOLD FREY, a citizen of the United States of America, residing at Chicago, in the county of Cook and State of Illinois, have invented certain new and useful Improvements in Hair-Cutting Implements, of which the following is a specification, reference being had therein to the accompanying drawings.

10 This invention relates to hair-cutting instruments, and more particularly to improvements in hair-clippers; and it has for its object to provide a clipper combined with a comb that will enable the barber to cut the hair any desired length; and with that object in view my invention consists in the construction and combination of parts, hereinafter described and claimed.

15 In the accompanying drawings, Figure 1 represents an elevation of my hair cutting instrument complete, and Fig. 2 a cross-section on line *x x* in Fig. 1.

Corresponding letters in the several figures of the drawings designate like parts.

20 A denotes the comb-plate, being a metal plate that has teeth like a comb and an elbow-extension, *b*, against the end of which is secured by rivets or screws the handle *B*. Upon the solid portion of the comb-plate is placed 25 the cutter-plate *C*, having triangular cutter-teeth *c*, and over plate *C* is placed a plate, *D*, of thin steel, having a rear rectangular flange, *d*, resting upon the rear edge of comb-plate *A*, and a forward rectangular flange, *e*, resting 30 upon the cutter-plate *C* in a manner that only the flanges form a bearing-surface and that the intermediate plate lies hollow. Screw-studs *f*, made rigid with comb-plate *A*, pass through longitudinal slots in the cutter-plate 35 *C*, and then with their screw-threaded points pass through holes in guide-plate *D*, and are provided with screw-nuts that with tightening will compress the forward flange, *e*, of guide-plate *D* upon the cutter-plate *C*, for holding 40 the cutter-teeth *c* close upon the roots of the comb-teeth *a* to form shearing-edges therewith.

The guide-plate *D*, being sufficiently thin to be elastic, will facilitate this shearing operation by holding the parts in close contact without excessively clamping the parts and without retarding the reciprocating movements of the cutter-plate *c*. The lever-handle *G* is pivoted at one side of its T-shaped end, between the extension *b* of comb-plate *A* and the end of handle *B*, on one of the rivets or screws that 50 secure said handle *B* to the comb-plate *A*, while the other side of said T-head of handle *G* forms a pivot-head, *g*, engaging a correspondingly-shaped notch, *h*, in the end of the cutter-plate *C* in a manner that a swinging movement of 55 handle *G* will transmit a reciprocating movement to said cutter-plate. Against the opposing ends of handles *B* and *G* are secured the ends of curved leaf-springs *I*, the opposite ends of which are notched to interlock each 60 other in a manner that the action of both springs *I* combined will force the handles *B* and *G* apart again after each compression.

A small handle, *J*, forms part of either the comb plate *A* or the guide-plate *D*, and serves 65 to hold and guide the instrument with the left hand while operating the clippers with the right hand.

What I claim is—

The combination, with the comb-plate *A*, 70 having the elbow-extension *b* at one end, of the cutter-plate *C*, mounted over the comb-plate and having the notch *h* in an extension at one end, the plate *D*, for holding and guiding the cutter-plate, and the handles *B* and *G*, the 75 former being secured to extension *b*, and the latter having a T-shaped inner end, one limb of which is provided with a pivot-head, *g*, working in notch *h* of cutter-plate, and the other limb being pivoted to the extension *b*, 80 as set forth:

In testimony whereof I affix my signature in presence of two witnesses.

ARNOLD FREY.
